UNITED STATES PATENT OFFICE.

ROBERT BELDEN, OF BELDEN, CALIFORNIA.

WASHING-MACHINE.

1,391,605.

Specification of Letters Patent. Patented Sept. 20, 1921.

Application filed March 14, 1921. Serial No. 451,992.

To all whom it may concern:

Be it known that I, ROBERT BELDEN, a citizen of the United States, residing at Belden, in the county of Plumas and State of California, have invented new and useful Improvements in Washing-Machines, of which the following is a specification.

My present invention has reference to a washing machine.

10 My object is to produce a device of this character wherein clothes will be washed and cleaned in an expeditious manner without liability of damage thereto.

15 A further object is to produce a washing machine in which the tub is provided with a false bottom of a novel construction, and in which the dasher members are in the nature of rollers that yieldably contact with the clothes arranged on the false bottom to circulate the water through the clothes and through apertures in the false bottom as well as effecting a slight bearing engagement on the clothes, not, however, sufficient to impart injury to the clothes.

20 25 Other objects and advantages will present themselves as the nature of the invention is better understood, reference being had to the drawings which accompany and which form part of this application, and in which:—

30 Figure 1 is a top plan view of a washing machine with the cover removed.

Fig. 2 is a sectional view on the line 2—2 of Fig. 1.

35 Fig. 3 is a sectional view on the line 3—3 of Fig. 2.

Fig. 4 is a view of the removable false bottom.

Fig. 5 is a bottom plan view of the dasher.

Fig. 6 is an elevation thereof.

40 As disclosed by the drawings, the tub 1, of my improved washing machine, is supported on equi-distantly spaced depending legs 2.

45 Two of the oppositely disposed legs are connected by a cross piece 3 on which there is centrally secured a bearing 4 for the ends of a horizontally disposed drive shaft 5 and a vertical driven shaft 6. The drive shaft 5 also finds a bearing in one of the legs disposed intermediate of the legs connected by the cross piece 3. The drive shaft has on its outer end a belt wheel or pulley 7 designed to receive a belt that is connected with any desired source of power. Of course, 50 if desired, the shaft 5 may be operated by hand, in which instance, the outer end thereof is cranked.

55 The drive shaft 5, at its bearing end is provided with a beveled pinion 8, and the driven shaft 6 has secured thereon a similar pinion 9 which, of course, meshes with the pinion 8.

60 The shaft 6 extends through a central opening 10 provided in a cross sectionally cylindrical post or column 11 that has its lower portion outwardly flared as at 12 and connected to the bottom 13 of the tub 1. Beyond the flared portion the column is preferably formed with a reduced extension 14 that is received in an opening in the bottom 70 of the tub. Arranged in the tub is a false bottom 15. The false bottom is in the nature of a disk, having an enlarged central opening 16 to permit of the same being arranged over the column and the flange at 75 the lower end thereof. The false bottom is provided with a spaced series of concentrically arranged apertures 17 and preferably has its periphery formed with spaced downturned flanges which provide 80 feet 18 that elevate the false bottom above the bottom 13 of the tub.

85 The column 11 is of a length less than the depth of the tub, and the shaft 6 has a cross sectionally squared end 19 that projects above the column. On this squared end there is received the head member 20 of the dasher of the improvement. The head 20 has a squared opening 21 therethrough, so that the same will be revolved when the 90 shaft 6 is turned. Pivotedly supported on the outer face of the head, at equidistantly spaced points which arrange the same at right angles with respect to each other, are the inner angle ends 21 of depending rods 95 22. Each of the rods is of an equal length and has its lower end offset and extended outwardly away from the head to provide shafts 23. On each of the shafts 23 there is journaled a roller 24 that provides the 100 dasher proper. The rollers are peripherally grooved, as at 25, but the grooves provided in one of the rollers may be spaced at a greater distance than the grooves provided in the adjacent rollers. Connecting each of 105 the rods 22 is a spring 26, whereby the rods are normally sustained vertically with respect to the tub. The springs permit an independent yielding of any of the rods and the rollers carried thereby without materi- 110

ally influencing the rods carrying the remaining rollers. This is a desired feature of the improvement, inasmuch as the roller dashers will pass over uneven surfaces in the clothes disposed in the tub to be washed.

5 The head 20 of the dasher is held against removal from the squared end of the shaft 6 through the medium of a removable element such as a pin 29 passing through the 10 outer end of the said shaft, but the pin is not normally in contact with the upper end of the head, so that the head, in addition to receiving a rotary movement on the shaft is permitted a limited longitudinal outward 15 movement thereon.

15 In operation, the dasher is removed from the shaft and the clothes inserted on the false bottom in the tub. The dasher is then arranged on the shaft 6. Of course, sufficient 20 saponaceous water is disposed over the clothes before the machine is operated, and the open top of the tub is also covered by a closure member 30. The shaft 5 is then revolved which, of course, causes the turning 25 of the shaft 6 and the dasher. The roller portion of the dasher members ride over the top of the clothes and exert a contacting engagement therewith, not, however, sufficient 30 to impart injury to the clothes. The rotary movement of the dasher causes a centrifugal action on the washing fluid, so that the same is continually circulated through 35 the clothes, below the false bottom, and through the apertures in the false bottom, thus causing all of the water to penetrate all of the clothes, and thus clean the clothes in an easy and expeditious manner.

Having described the invention, I claim:—

1. In a washing machine, a tub, a central 40 column therein, a shaft extending through the column, a dasher including a removable head, disposed on the shaft, resting on the upper end of the column, revoluble with the shaft and susceptible to a limited longitudi-

nal movement thereon outward of the column, rods having oppositely disposed angle ends, one end of each rod being pivoted to the head, a grooved roller journaled on the opposite end of each rod, and means for revolving the shaft. 45

2. In a washing machine, a tub, a central column therein, a shaft extending through the column, a dasher including a removable head disposed on the shaft, resting on the upper end of the column, revoluble with the shaft and susceptible to a limited longitudinal movement thereon outward of the column, rods having oppositely disposed angle ends, one end of each rod being pivoted to the head, a grooved roller journaled on the opposite end of each rod, spring means retaining the rods in predetermined relation to each other, and means for revolving the shaft. 50

3. In combination with a tub, of a hollow cylindrical column extending upwardly through the bottom of said tub and having an outwardly flared portion secured to the bottom of said tub, a disk surrounding the flared portion of said column and provided 65 with a plurality of openings, a plurality of depending flanges extending from said disk and engaging the bottom of said tub, a shaft extending through said column and provided 70 with a squared upper end, a head provided 75 with a longitudinal squared opening surrounding the squared end of said shaft, a pin extending through the upper end of said shaft, a plurality of vertical rods provided with oppositely directed horizontally 80 disposed offset ends and pivotally secured to said head at right angles to each other, grooved rollers mounted on said rods, a plurality of coil springs connecting said rods 85 and means for rotating said shaft. 85

In testimony whereof I affix my signature.

ROBERT BELDEN.
